UNITED STATES PATENT OFFICE

2,535,803

TELESCOPIC STANDARD OR ARM

Frants Heinrich Maack, Odense, Denmark

Application July 26, 1947, Serial No. 763,787
In Denmark October 3, 1945Section 1, Public Law 690, August 8, 1946
Patent expires October 3, 1965

4 Claims. (CL. 248—161)

1

The invention relates to a telescopic standard or arm for an organ consuming electric current, for instance a lamp mounted at one end of the standard with its conductors carried through the latter to the other end of the standard which is fastened in a centrally located aperture in a receptacle, for instance, a lamp base into which the conductors are pushed upon the standard being telescoped, characterized by guiding-devices through which the part of the conductors situated at any time in the receptacle will automatically occupy—without the employment of guide-rolls or the like movable guide-members—upon the standard being telescoped, a pre-arranged, evenly curved position, preferably coiling in windings similar to those of a rope-coil.

Standards or arm are known where a resilient steel tape, slightly curved transversal to its longitudinal direction, supports the electric organ and is arranged to be pushed, simultaneously with its coiling, into a cylindrical house in a manner similar to that of automatically unwinding steel tape meters. Also, hoisting-lamps are known where the conductors are coiled, upon the lamp being pushed together, on a system of rolls in a receptacle. These known constructions are, however, most complicated and require, for instance, drums acted upon by springs for the coiling-up of the conductors, or they are clumsy and inefficient, as the outer form of the whole apparatus is to such an extent dependent upon and restricted by the construction that the esthetic and practical demands to the article for use in question can ordinarily not be fulfilled.

By the invention a light and elegant design is achieved that, furthermore, is inexpensive of production and massive and sturdy when employed. By an adequate form of construction according to the invention the conductor is arranged to be elastically bent and twisted to such an extent that it may be coiled-up in regular, spiral or screw-formed windings along the bottom or side-walls of the stationary receptacle, as the conductor, upon the telescoping of the standard, is pushed into the receptacle through a centrally arranged aperture of entering, hereby being essentially directed according to the axis of the windings, the drawn-out part of the standard having simultaneously sufficient supporting power and rigidity to support the electric organ at the momentary position of extension.

According to the invention the receptacle for housing the conductor may be located at one end of the standard, for instance, forming a base for the latter, or be intersecting the standard, in

2

which latter case the conductor may be pushed into the receptacle from either side. Furthermore, the conductor may according to the invention be enclosed by a spiral spring one end of which is fastened in the receptacle, the organ consuming electric current being fastened to its other end. The spiral spring may be of such rigidity as to enable its extended part to replace the standard, but according to the invention the conductor, with or without a spiral spring, may be enclosed, at its length outside the receptacle, by a telescopic tube, known per se, fastened at one end to the electric organ. In this case the conductor, or the spiral spring enclosing it, may by means of its friction detain the standard in its momentary extended position, or a special drag-spring coupling may according to the invention be employed in the telescope connection, besides which may be arranged a special, possibly releasable, friction device for the standard and the conductor, or the spiral spring enclosing it may according to the invention have such tension that it will automatically emerge from the receptacle upon the friction device being released. In such cases where the conductor is arranged rather loosely in a spiral spring, a certain friction will take place between conductor and spring. In order to prevent the conductor from forming kinks in such cases that may be squeezed and cause the conductor to be ruptured, a cavity may according to the invention be arranged immediately below the holder of the organ with a spring fastened to the conductor and arranged in such a manner that it will tend to keep the conductor tightly extended within the spiral spring, as the cavity will offer a space for the bights produced in this way.

Further characteristics according to the invention will appear from the claims and the following description of the forms of construction shown on the drawing, where

Figure 1 shows, in side view, a lamp with spiral-spring standard in telescoped position.

Figure 2, same in partly extended position, partly in section,

Figure 3, horizontal section through base of same,

Figure 4, a bracket lamp with circular-curved telescope arm, in side view, and

Figure 4a, a longitudinal section through the base of a lamp with special guiding-device for the conductors.

In Figures 1-3, 1 represents a receptacle serving as a base for the lamp and in the form of a low cylinder with a centrally arranged tube socket 2,

In receptacle 1 the end of a tightly wound spiral spring 4 is fastened by means of clamp 3, the spring being carried out through tube socket 2, its other end being fastened to lamp socket 5. An electric conductor 6 is carried through spiral spring 4 to the lamp socket. As indicated in Figures 2 and 3 spiral spring 4 is placing itself, on being introduced into receptacle 1, in regular spiral windings and, in extended position, it is of sufficient rigidity to detain lamp socket 5 with lamp, etc., in an adlibitive position of extension, as the friction at tube socket 2 is sufficient to prevent the spiral spring from being drawn out of or pushed into receptacle 1.

In Figure 4 a bracket lamp is shown where a telescopic arm formed by three circular-curved tubes 8-10 is fastened to receptacle 1, the latter serving as a base plate, the arm carrying at its end a lamp socket 11. Through telescopic arm 8-10 a conductor of suitable stiffness has been drawn, at one end fastened to receptacle 1 and, upon the telescoping of the arm, placing itself in regular windings in receptacle 7 in a manner corresponding to that described above for spiral spring 4. The conductor may be enclosed in a spiral spring at a tight fit, the spring possibly serving as part of the insulation- and wearing-cover of the conductor. In the case that the conductor is lying loosely in the spiral spring it may be wound in screw-form, preferably in windings principally following the windings of the spring. In this manner the mutual friction by a long extension between spring and conductor is distributed uniformly, whereby the conductor is protected from local abuse.

In Figure 4a the end of a telescope tube 31 is fastened in front of the central hole in a lamp base 32 through being screwed onto the end of a tube 34 provided with flange 33 for fastening. Tube 34 has an even curve and its other is carried out through the side-wall of lamp base 32 and fastened in this place by means of end-sleeve 35 and fastening-sleeve 36. The conductors 37 drawn through the standard are carried through tube 34 which guides the part of the conductors located in base 32 in such manner that, upon the telescoping of the standard, they are carried in an even curve through the base and out of the aperture in the side-wall of the latter.

Steel or other metal, or an adlibitive artificial substance of suitable strength and elasticity may be employed as material for the spiral springs and the like used in the invention, and instead of the spiral spring enclosing the conductor an elastic, flexible tube-hose of other construction may be employed.

Having thus described my invention, what I claim is:

1. A telescopic standard comprising a plurality of tubes surrounding each other, the widest one being fastened to a receptacle forming the base of said standard, which extends from a central hole in the upper wall of said receptacle, said standard carrying at its upper end an electric current consuming device, needing an insulated current-feeding cable, the cable feeding said device being led through said standard and said hole into said receptacle, whence it can be connected to a source of electricity, said cable being insulated from but surrounded by a tightly wound helicoidal spring, one end of said spring being fastened to the upper end of the standard and the other end thereof being fastened inside of said receptacle laterally with respect to said central hole, the spring when the standard is pushed together coiling regularly to form a uniplanar helix, the axis of which is parallel to said standard, whilst maintaining said cable substantially immobile relative to said spring, whereby the utilized cable length remains constant.
- 15 2. A standard as set forth in claim 1, the spring coiling to form a flat spiral, the plane of which is at right angles to the standard.
- 30 3. A standard as set forth in claim 1, the portion of the cable surrounded by the helicoidal spring having a greater length than said spring.
- 35 4. A standard as set forth in claim 1, the cable surrounded by the helicoidal spring being also wound helically, whereby the windings of said cable substantially follow the windings of said spring.

FRANTS HEINRICH MAACK.
